UNITED STATES PATENT OFFICE.

JASPER BATES, OF THORNBURY, ONTARIO, CANADA.

MANUAL POWER.

SPECIFICATION forming part of Letters Patent No. 278,306, dated May 29, 1883.

Application filed March 23, 1883. (No model.)

To all whom it may concern:

Be it known that I, JASPER BATES, of Thornbury, in the county of Grey, in the Province of Ontario, in the Dominion of Canada, have invented certain new and useful Improvements in Manual Powers; and I do hereby declare that the following is a full, clear, and exact description of the same.

This invention consists of a machine in which a compound lever is worked by the hands, feet, and seat of the operator for driving machinery having either a reciprocating or a rotary motion.

Figure 1 is a perspective view of my improved machine; and Fig. 2 is a vertical section of the same, showing its motion in dotted lines.

A is the base-plank, raised from the ground upon transverse feet B, which support the machine in a standing position.

C C are parallel vertical posts, footed to the base A, and connected at top by cap D, having a central hole, through which passes the stem E of a seat, F, on which the operator sits. The lower end of stem E bears upon one end of a horizontal lever, G, fulcrumed between posts H H, secured to base A. The opposite end of the lever G connects, pivotally, with the end of a horizontal leg of an elbow-lever, I, which is fulcrumed at its angle to posts J J, secured to base A. In a slot in the upper end of the vertical leg of lever I is pivoted the shaft of a handle, K, extending toward the seat F. The pin connecting levers G I projects on opposite sides of the levers and carries foot-rests L. The pin works in an elongated hole in one of the levers, whereby both levers will have play motion at the point

of connection to tilt above and below a horizontal position, as seen in Fig. 2.

O is a brace to strengthen the angle or elbow of lever I; and P is a pitman pivoted to lever I, to connect horizontally with the mechanism to be driven. Q is a removable bar, attached to horizontal arm of lever I by thumbscrew N, to obtain a long vertically-operating stroke, if required; or the attachment of the mechanism to be driven may be to any moving part of my machine and in any suitable manner.

When the operator depresses the seat the connected ends of levers G I rise and pivotally throw forward the vertical arm, to which the pitman is connected, and when the operator transfers his weight onto his feet, placed on rests L, the depression thereby of the connected ends of the levers will raise the seat and recede the vertical arm, thus performing a full stroke to drive the connected machinery. The operator grasps the handle K, and exerts muscular power in the direction required without moving from his seat.

I claim as my invention—

The combination, with posts C C, H H, and J J, footed to base A, of the seat E, having vertical stem F, straight lever G, elbow-lever I, foot-rests L, and handle K to operate in the manner set forth.

In witness thereof I have hereunto set my hand in the presence of the two undersigned witnesses.

J. BATES.
